UNITED STATES PATENT OFFICE.

LAURENCE A. SCHNEIDER, OF CANTON, OHIO, ASSIGNOR TO CANTON FORGE & AXLE COMPANY, OF CANTON, OHIO, A CORPORATION OF DELAWARE.

APPARATUS FOR MANUFACTURING RAIL ANCHORS.

Application filed September 29, 1924. Serial No. 740,593.

My invention relates to apparatus for manufacturing rail anchors of sheet metal. The primary object of the invention is to provide a new and improved apparatus for manufacturing devices of the above character, whereby the rail gripping jaws and the interlocking portions of the anchor members may be made with a high degree of accuracy by bending metal blanks to the desired configuration, and whereby the bending of said blanks, even though the portions bent be relatively short, may be effected with a minimum stretch of metal.

A further object is to provide new and improved constructions, arrangements and devices in an apparatus hereinafter described and claimed for carrying out the above stated object and for accomplishing such other objects as will appear from a description of the invention shown in the annexed drawings.

In the drawings,

Fig. 1 is a plan view of a portion of a railroad rail and cross tie showing one form of rail anchor that may be formed with my improved apparatus;

Fig. 2 is a face view of the rail anchor shown in Fig. 1, the base portion of the rail being shown in section;

Fig. 3 is a view in perspective of one of the rail anchor members;

Fig. 4 is a view in perspective of another rail anchor member adapted to have an interlocking engagement with the member shown in Fig. 3;

Fig. 5 is a front view in elevation of my preferred form of apparatus used in connection with the manufacture of the rail anchor members shown in Figs. 3 and 4;

Fig. 6 is a plan view of the base portion of the machine;

Fig. 7 is a fragmentary view in elevation showing the die sections employed in connection with certain bending operations in the manufacture of the member shown in Fig. 3;

Fig. 7a is a plan view of a sheet metal blank from which the member shown in Fig. 3 is formed;

Figs. 8 and 9 are side views in elevation showing the dies and associated parts of the apparatus used in connection with the finishing operations of the member shown in Fig. 3;

Fig. 10 is a view in perspective of a sheet metal blank from which the anchor member shown in Fig. 4 is formed, a portion of the blank being illustrated in this figure as being bent to a position to provide a tie abutment for the anchor;

Figs. 11 and 12 are views in elevation of the blank and the die sections employed for forming certain bends in the blank; and

Figs. 13 and 14 are views in elevation showing the dies and associated mechanism of the apparatus for performing the finishing operation in connection with the manufacture of the anchor member shown in Fig. 4.

My improved apparatus, to be hereinafter described, is particularly suitable for use in the manufacture of a sheet metal anchor of the two piece type shown in Figs. 1 to 4 inclusive of the drawings, but may, obviously, be used in connection with the manufacture of other types of anchors where similar conditions are present.

The rail anchor illustrated in the drawings is a device consisting of two jaw members 10 and 11 which grip opposite edges of the rail base 13 and have a wedging interlocking engagement with each other at a point beneath the base of the rail. The member 10 of the anchor is formed at one end with a jaw portion 14 adapted to grip one edge of the rail base, which jaw portion is so formed as to provide recesses 15 and 16 to provide clearance for the upper and lower corners of the rail base, and thereby insure a firm bearing engagement of the jaw 14 and the body portion of the member with the upper and lower surfaces respectively of the rail base. The other end of the anchor is bent to provide a channel shaped portion 17, the upstanding flange 18 of which is relatively low and extends at an angle to the longitudinal center of the rail so as to function as a wedge when the same is interlocked with the mating member 11. The flange 18 is preferably bent inwardly so as to stand at an angle to the vertical, so as to provide a hook-shaped configuration. At a point intermediate the jaw and said channel shaped portion, a projection is bent downwardly to provide an abutment 19 adapted to bear against a vertical face of the cross tie 20.

The member 11 is formed from a sheet

2

metal blank of the configuration shown in Fig. 7^a, bent to provide a jaw portion 21 for engaging the opposite edge of the rail. The jaw portion of this member, like the 5 jaw portion of member 10, is provided with recesses 22 and 23 to provide clearance for the upper and lower corners of this edge of the rail base and thereby insures a firm contact of the jaw 21 and the body of the member with the upper and lower surfaces of the rail base at a point within the edges of the base. The extremity of the jaw 21 is also preferably curved upwardly, as shown at 24. The other end of the member 11 is 10 formed with a downturned flange 25 of substantially the same height as the flange 18 and extends at an angle to the longitudinal axis of the rail so as to cooperate with the wedging surface of the flange 18. The 15 flange 25 is also inclined vertically so that the flanges 18 and 25 will provide an interlocking engagement to prevent the channel shaped portion of the member 10 from moving downward with relation to the under 20 surface of the rail base. The member 11 is preferably made of slightly thicker material than the member 10 so as to provide a relatively thick portion or striking surface to receive the hammer blows during the application of the anchor to a rail.

The anchor is applied to the rail by hooking the jaws of the members 10 and 11 over opposite edges of the rail base. The member 11 is then driven longitudinally of the rail so that the angularly disposed flanges 18 and 25 of the members will effect a firm wedging engagement with each other and thereby produce a tight gripping action of the jaws 14 and 21 upon the opposite edges 40 of the rail base.

In Figs. 5, 6, 7, 8, and 9, I have shown my improved apparatus, including the die sections and cooperating mechanism adapted for use in connection with the manufacture of the rail anchor member 11. The apparatus illustrated consists of a base 26 formed with upstanding guide members 27. A crank shaft 28 is journaled in bearings 29 at the upper end of the guides 27 and is 45 connected by means of a connecting rod 30 to a reciprocating head 31. The head 31 operates between the guides 27 and carries on its lower surface die sections 32 and 33 which sections cooperate with die sections 32^a—33^a secured to the base to bend the blank 34 (Fig. 7^a) to the desired configuration. The operation of the reciprocating head 31 is controlled by a treadle clutch mechanism 28^a.

60 After the blank 34 is heated to a suitable bending temperature, it is bent to the configuration shown in Fig. 7 by means of the die sections 32—32^a. The final bending operations to which the blank is subjected are 65 accomplished by means of the die sections

33—33^a and the mechanism associated therewith, to be hereinafter described. The die sections 32 and 33, it will be observed, are carried on a single reciprocating head, so that two blanks may be operated upon simultaneously, that is to say, that the initial bending of one blank and the finishing operations on another are performed simultaneously so that one completed anchor member may be made for each working stroke of the machine.

The die sections 32—32^a are formed with oppositely disposed surfaces 35—35^a which, when the die sections are brought together, bend the blank to its initial or partially formed contour as shown in Fig. 7 of the drawings. The point 36 of the die section 32 is of such configuration as to form the clearance recess 23 of the member 11 shown in Figs. 2 and 3. During the initial bending operation the end 37 of the blank is bent over the rib 38 of the die section 32^a and pressed firmly against its side 39 so as to form the inclined flange 25 of the anchor member. The curved surface 40 of the die section 32 is so proportioned as to insure the pressing of the end 37 of the blank firmly against the surface 39 of the die section 32^a and thereby insure a uniform inclination of the flange 25 of the finished member. The rib 38 of die section 32^a is so disposed that the bending of the end 37 of the blank will be effected as previously mentioned, along a line parallel to the diagonal edge 41 of the blank. Reference numeral 42 designates a stop member against which the blank 34 is positioned so as to insure the proper positioning of the blank on the die section 32^a. The proper position of the blank is indicated in dotted lines in Fig. 7.

After the blank is bent to the configuration shown in Fig. 7, it is positioned as shown in Fig. 8, upon the anvil 43 of the die section 33^a and held firmly on the anvil during the finishing operations by means of a dog 44. The dog 44 is formed at one end with an angular portion 45 corresponding to the configuration of the flanged end portions of the partially formed flange and is pivoted at the other end by a pin 46 to the die section 33^a. The dog is normally held in elevated position by means of a spring 47 and is moved to a blank holding position by means of a cam member 48 which projects downwardly from the die section 33 so as to engage the corner 49 of the dog. The angular end of the dog 44 is pressed against the blank by means of a spring plunger 50 carried by the die section 33 and is held in such position by means of such spring plunger and the engagement of the flat surface 50^a of the dog with the surface 51 of the cam member 48.

The end of the anvil 43 is formed with an enlargement, one portion 52 of which fits

into the recess 23 formed in the blank by the end 36 of the die 32. The other portion 53 of said enlargement forms the clearance recess 22 of the anchor member when 5 the end 54 of the blank is bent to its completed form. The end 54 of the blank is bent around the die 43 by means of an arm 55 pivoted at 56 to the die section 33 and formed at the other end with a rounded 10 portion 57 which engages the blank. The arm 55 is guided between canways 58 of the die section 33^a and is provided with rollers 59 which roll upon the cam surfaces 58 when the die section 33 is moved from the 15 position shown in Fig. 8 to the position shown in Fig. 9.

The finished anchor member is removed from the anvil by means of a kick-off mechanism consisting of a slide 60 normally held 20 in its inoperative position by means of a spring 61. The slide 60 has a sliding connection 62 with a pivoted dog 63 adapted to be rocked to move the slide toward the anvil when the reciprocating head 31 of the 25 machine approaches its extreme upper position. The rocking movement of the dog 63 is effected by means of an arm 64 pivoted to the head 31 so as to pass over the dog 63 during the downward stroke of the head 30 31, but which engages with the dog 63 and rocks the same when the head approaches the limit of its upward stroke.

When manufacturing the member 10 of the rail anchor illustrated herein, a blank 35 65 of the configuration shown in Fig. 10 is sheared from a metal sheet of the desired thickness, the end 66 of the blank being sheared on a diagonal line and the blank being provided along its longitudinal edge 67 40 with a portion 68. The blank is heated to a suitable bending temperature and is subjected while it is hot to a plurality of bending operations, all bending operations being preferably completed with a single heating 45 of the blank. The first of the bending operations consists in bending the portion 68 to a right angle with respect to the body portion, so as to provide the tie abutment 19 of the anchor, shown best in Fig. 2 of 50 the drawings. The next of the bending operations consists in offsetting the body portion of the blank laterally and bending one end thereof upwardly to the configuration shown in dotted lines in Fig. 11. The di- 55 55agonal end 66 of the blank is then bent upwardly and outwardly so as to partially form a channel shaped portion 17 of the anchor. The next and final bending operation consists in bending the end 66 of 60 the blank to its finished position, so as to provide the inclined flange of the anchor member, and the bending of the upstanding portion 69 at the other end of the blank to provide the rail engaging jaw 14 of the 65 anchor member.

The portion 68 of the blank may be bent to the position shown in Fig. 10 by any suitable means, for example, by means of suitable die sections secured to the machine in the manner disclosed in connection with 70 the manufacture of the member 11, of the anchor. The other bending operations above mentioned are performed preferably by means of die sections 70—70^a, 71—71^a, and 72—72^a. The upper die sections 70, 71, and 75 72, are secured to the reciprocating head 31 of the machine, and the lower die sections 70^a, 71^a, and 72^a are secured to the base of the machine in substantially the same manner as that shown in connection with the 80 die sections employed in the manufacture of the member 11 of the anchor.

The die sections 70—70^a are formed with cooperating faces of substantially the contour shown in Fig. 11. The blank is supported in a diagonal position on the shoulders 73 and 74 of the die section 70^a with the diagonal edge 66 of the blank resting on the diagonal face 75 of the die section. The blank is then pressed between the die sections to offset the body portion of the blank laterally and bend the end 69 thereof upwardly, substantially as shown in the dotted lines in Fig. 11. The bent blank is then positioned upon the die section 71^a, in which position the end 66 of the blank rests on a curved shoulder 76 of the die section 71^a, and the bend 78 at the other end of the blank rests upon the curved surface 79 of said die section. The die section 71 is provided with a projection 80 which, when the section 71 is moved downward, engages the angular portions 81—82 of the blank and presses them into a recess 83 of the die section 71^a to partially form the channel shaped portion 17 of the anchor member. When the die section 71 reaches the limit of its downward movement, it presses the blank firmly against the walls of the recess 83 and against the surface 84 of the die section 71^a. The projection 80 and the recess 83 taper in width so as to form the bend 85 of the blank on a line parallel to the diagonal edge 66, thereby forming the upstanding flange of the anchor of uniform height throughout. The other bends in the body portion are preferably formed on lines perpendicular to the longitudinal edges of the blank. The blank is then placed in an inverted position on an anvil portion 86 of the die section 72^a. The anvil 86 is formed at one end with a portion 87 corresponding in contour to the inner wall of the channel shaped portion 17 of the finished anchor member, and is formed at the other end with curved portions corresponding substantially to the contour of the jaw end of the anchor member. The end 66 of the blank is bent inwardly and pressed firmly against the wall 88 of the anvil by means of a dog 89 pivoted at its lower end to the die 115 120 125 130

section 72^a by a bolt 90 and formed on its inner face with a recess 91 of such contour as to bear against the entire outer surface of the end 66 and also extend around the bend 85 of the blank so as to press the channeled portion of the blank against the upper surface 92 of the anvil. The pivoted dog 89 is normally held in inoperative position by means of a spring 93 and is moved into engagement with the blank by means of a cam member 94 carried by die section 72. The member 94 is provided with a cam surface 95 which bears against the dog to swing it inwardly when the die section 72 moves 15 downwardly from the position shown in Fig. 13 to the position shown in Fig. 14. When the dog 89 is moved to the limit of its working stroke, it is held in such position during the subsequent bending of the blank by 20 means of an engagement of the rear face 96 of the dog with a vertical inner face 97 of the cam member 94.

The end 69 of the blank is bent around the end 98 of the anvil to provide the jaw portion 14 of the finished anchor member. This end of the anvil is formed with beads 98' and 99 which provide for the forming of the clearance recesses 15 and 16, respectively, of the anchor member. The bending of the end 30 69 of the blank is accomplished by means of a pivoted arm 100 carried by the upper die section 72 and formed at its lower end with a rounded angularly disposed portion 101, which engages the end 69 of the blank. The lower end of the arm 100 is provided on opposite sides with rollers 102, which bear on curved cam surfaces 103 of the die section 72^a. 104 designates a die form carried by die section 72, the lower face 105 of which 40 is so formed as to bear against the blank and press it firmly against the surfaces 92, 106, and 107 of the anvil when the die section 72 reaches the extremity of its downward stroke. The pressure of the die portion 104 against the blank, presses the blank firmly around the bead 99 of the anvil. The die sections for bending the portion 68 of the blank to provide the tie abutment and also the die sections for performing the other 50 bending operations may all be suitably arranged on one machine, grooves for the attachment of the dies being shown in the base and in the head 31 of the machine in Fig. 5, so that the several bending operations may 55 be performed on different blanks during the same stroke of the reciprocating head 31 of the machine, thereby making it possible to finish one complete member of the anchor for each operating stroke of the machine, thereby permitting, by the close arrangement 60 of the die sections, the shifting of the several blanks from one die section to another with a minimum length of time so that the blanks when subjected to the final bending operation, will be of sufficiently high tem-

perature to insure that these final bending operations will be made with a high degree of accuracy.

While I have described my invention in connection with dies suitable for use in the manufacture of one type of rail anchor, it will be understood that I contemplate all modifications in structure that come within the scope of the appended claims.

I claim:

1. An apparatus of the character described, comprising a die section adapted to receive a metal blank, a member pivoted to move into engagement with the blank to hold the same on said die section, a reciprocating member provided with means for moving said pivoted member into engagement with said blank, means on said reciprocating member for exerting pressure against said blank, and a pivoted element on said reciprocating member for engaging an end of said blank to bend the same around a portion of said die.

2. An apparatus of the character described, comprising a die section adapted to receive a metal blank, a member pivoted to move into engagement with the blank to hold the same on said die section, a reciprocating member provided with a cam element for moving said pivoted member into engagement with said blank, means on said reciprocating member for exerting pressure against said blank, and a pivoted element on said reciprocating member for engaging an end of said blank to bend the same around a portion of said die.

3. An apparatus of the character described, comprising a die section adapted to receive a metal blank, a member pivoted to move into engagement with the blank to hold the same on said die section, a reciprocating member provided with a cam element for moving said pivoted member into engagement with said blank and for holding said member in operative engagement therewith, means on said reciprocating member for exerting pressure against said blank, and a pivoted element on said reciprocating member for engaging an end of said blank to bend the same around a portion of said die.

4. An apparatus of the character described, comprising a die section adapted to receive a metal blank, a member pivoted to move into engagement with the blank to hold the same on said die section, a reciprocating member provided with means for moving said pivoted member into engagement with said blank, means resiliently yieldable on said reciprocating member for exerting pressure against said blank, and a pivoted element on said reciprocating member for engaging an end of said blank to bend the same around a portion of said die.

5. An apparatus of the character described, comprising a die section adapted to

70

receive a metal blank, a member pivoted to move into engagement with the blank to hold the same on said die section, a reciprocating member provided with means for 5 moving said pivoted member into engagement with said blank, means resiliently yieldable on said reciprocating member and adapted to bear upon said pivoted member for exerting pressure against said blank, and 10 a pivoted element on said reciprocating member for engaging an end of said blank to bend the same around a portion of said die.

6. Apparatus of the character described, 15 comprising a stationary die member adapted to receive a metal blank, a member pivoted to move into engagement with said blank, cam mechanism for actuating said pivoted member, a pressure member adapted to bear 20 against said pivoted member, and a pivoted dog adapted to engage one end of the blank to bend the same around a portion of said die.

7. Apparatus of the character described, 25 comprising a stationary die member adapted to receive a metal blank of angular configuration, a member pivoted to said die member and adapted to move into engagement with said blank, cam mechanism for actuating 30 said pivoted member, a pressure member adapted to bear against said pivoted member, and a pivoted dog adapted to engage one end of the blank to bend the same around a portion of said die.

35 8. Apparatus of the character described, comprising a stationary die member adapted to receive a metal blank of angular configuration, a member pivoted to said die member and adapted to engage one end 40 of the blank to bend it against the die member, cam mechanism for actuating said pivoted member, a pressure member adapted to bear against said pivoted member, and a pivoted dog adapted to engage the other end 45 of the blank to bend the same around a portion of said die.

9. Apparatus of the character described, 50 comprising a stationary die member adapted to receive a metal blank, a pivoted member secured to said stationary die and adapted to move into engagement with one end of said blank to bend the same around a portion of said die member, a reciprocating cam member formed with an angular surface 55 adapted to move said pivoted member into engagement with the blank and formed with a vertical face for engaging said pivoted member and holding it in its operative position, a pressure member adapted to bear 60 against said pivoted member, and a pivoted dog adapted to engage the other end of said blank to bend the same around a portion of said die.

10. An apparatus of the character de- 65 scribed, comprising a stationary die member

adapted to receive a metal blank, a member pivoted at one end to said die member and formed at the other end with a blank pressing surface corresponding in contour to a portion of said blank, a reciprocating member provided with a cam element adapted to move said pivoted member to its blank pressing position, means on said reciprocating member for engaging one end of the blank to bend it around the die.

11. Apparatus of the character described, 70 comprising a stationary die member adapted to receive a metal blank, a member pivoted at one end to said die member and formed at the other end with a blank pressing surface corresponding in contour to a portion of said blank, a reciprocating member provided with a cam element adapted to move said pivoted member to its blank pressing position, and means comprising a pivoted arm 75 on said reciprocating member for engaging one end of the blank to bend it around the die.

12. Apparatus of the character described, 80 comprising a stationary die member adapted to receive a metal blank, a member pivoted at one end to said die member and formed at its other end with a blank engaging surface, a reciprocating member adapted to exert pressure against said blank and provided with a cam element adapted to move said pivoted element into its blank engaging position, and means comprising a pivoted arm 85 on said reciprocating member for engaging one end of the blank to bend it around a portion of said die.

13. Apparatus of the character described, 90 comprising a stationary die member adapted to receive a metal blank, a member pivoted at one end to said die member adapted to be moved into engagement with said blank, a reciprocating member provided with a cam element adapted to move said pivoted member to its blank engaging position, means 95 comprising a pivoted arm on said reciprocating member for engaging one end of the blank to bend it around a portion of the die, and means on said stationary die for guiding the lower end of said pivoted arm in a curved path.

14. Apparatus of the character described, 100 comprising a stationary die member adapted to receive a metal blank, a member pivoted at one end to said die member and adapted to be moved into engagement with said blank, a reciprocating member provided with a cam element adapted to move said pivoted member to its blank engaging position, means comprising a pivoted arm on 105 said reciprocating member for engaging one end of the blank to bend it around a portion of said die; said stationary die being provided with a cam surface for guiding the lower end of said arm in a curved path.

15. Apparatus of the character described 110

70

75

80

comprising a stationary die member adapted to receive a metal blank, a member pivoted at one end adapted to engage a portion of said blank to press the same firmly against the die, a reciprocating member provided with a cam adapted to move said pivoted member to its blank engaging position and to hold the same in said position, means comprising a pivotal arm on said reciprocating member for engaging one end of the blank to bend it around a portion of the die, the lower end of said arm being provided with rollers and said stationary die being provided with cam surfaces for said rollers and adapted to guide the lower end of said arm in a curved path.

16. Apparatus of the character described comprising a stationary die member adapted to receive a metal blank, a member pivoted at one end adapted to be moved into engagement with said blank to hold the same in position on said die, a reciprocating member for moving said pivoted member into engagement with said blank, an arm pivoted at its upper end to said reciprocating member and adapted to engage at its lower end a portion of said blank to bend it around a portion of the die, the said die member being provided with a curved cam surface and the lower end of said arm being provided with means engaging said cam surface of the die whereby said lower end of said arm is guided in a curved path.

17. Apparatus of the character described, comprising a stationary die member adapted to receive a metal blank, a member pivoted at one end adapted to be moved into engagement with said blank to bend a portion of the blank against the die and to hold the same in position on said die, a spring for normally holding said pivoted member in its inoperative position, a reciprocating member for moving said pivoted member into engagement with said blank, an arm pivoted at its upper end to said reciprocating member and adapted to engage at its lower end a portion of said blank to bend it around a portion of the die, the die member being provided with a curved cam surface and the lower end of said arm being provided with means engaging said cam surface of the die, whereby said lower end of said arm is guided in a curved path.

18. Apparatus of the character described, comprising a stationary die member adapted to receive a metal blank, a member pivoted at one end adapted to be moved into engagement with said blank to bend a portion of

the blank against the die and to hold the same in position thereon, a spring for normally holding said pivoted member in its inoperative position, a reciprocating member for moving said pivoted member into engagement with said blank, means carried by said reciprocating member for pressing the blank against the upper face of said die, an arm pivoted at its upper end to said reciprocating member and adapted to engage at its lower end a portion of said blank to bend it around said die, the said die member being provided with a curved cam surface and the lower end of said arm being provided with means engaging said cam surface of the die, whereby said lower end of said arm is guided in a curved path.

19. Apparatus of the character described, comprising a stationary die member provided with a beaded end portion and adapted to receive a metal blank, a member pivoted at one end adapted to be moved into engagement with said blank to bend a portion of the blank against the die and to hold the same in position on said die, a reciprocating member for moving said pivoted member into engagement with said blank, means carried by the reciprocating member for pressing the blank against the upper face of the die, an arm pivoted at its upper end to said reciprocating member and adapted to engage at its lower end a portion of said blank to bend the same around the beaded portion of said die, the said die member being provided with a curved cam surface and the lower end of said arm being provided with means engaging said cam surface of the die whereby said lower end of said arm is guided in a curved path.

20. In apparatus of the character described, the combination with a base portion, of a reciprocating head, separable die sections secured to said base and head respectively and adapted to exert pressure on metal blanks to form preliminary bends therein, a finishing die including means for performing the final bending operation, and mechanism for removing the work from the finishing die comprising a slide formed with projections adapted to extend over a portion of said finishing die, a pivoted dog having a sliding connection with said slide, and means carried by said head and adapted to engage said dog to rock the same when the said reciprocating head approaches its inoperative position.

LAURENCE A. SCHNEIDER.
